ANTENNA

Henry J. Riblet, Cambridge, Mass., assignor, by
mesne assignments, to the United States of
America as represented by the Secretary of War

Application November 6, 1945, Serial No. 627,040

7 Claims. (Cl. 250—33)

1

This invention relates to antennas for communication systems and more particularly to an antenna for use as a beacon in connection with radio-object locating systems.

Heretofore it has been considered necessary, in order to obtain uniform omnidirectional radiation of energy, more particularly of horizontally polarized energy, that a beacon antenna be radially symmetrical in cross-section. It has now been found, according to this invention that substantially uniform omnidirectional radiation in a plane may be obtained with an antenna asymmetrical in cross-section such as of streamlined, tear-drop, or even of rectangular shape in cross-section. Such an antenna has several advantages, i. e. when tear-drop or streamlined in shape, it avoids the necessity of a streamlined plastic housing which has a deleterious effect on the radiation patterns produced by known types of beacon antennas, it permits of several feed lines for a plurality of antenna radiating arrays within the same structure and, as a separate array may be used for transmitting or receiving, a transmit-receive switch or box may be omitted. The latter advantage also applies to a rectangular antenna which has the additional advantage of permitting end-abutted antennas to be fed and which also avoids the necessity of matching rectangular waveguide feed lines to circular antenna elements.

It is an object of the present invention to provide a novel antenna which embodies the aforementioned advantages and overcomes the unsatisfactory features heretofore existing with radially symmetrical antennas.

It is another object of this invention to provide a beacon antenna having a streamlined, tear-drop or other non-circular shape, including rectangular, in cross-section and which is capable of producing a substantially uniform omnidirectional radiation pattern in a plane perpendicular to the longitudinal axis of the antenna.

It is still another object of the invention to provide an antenna structure which is non-circular in cross-section and which is adapted to radiate horizontally polarized energy in a substantially uniform omnidirectional pattern in azimuth when in its contemplated vertical position.

For a better understanding of the invention together with other and further objects thereof, reference is had to the following description, taken in connection with the accompanying drawings, wherein like parts are designated by like reference numerals, and in which:

2

Fig. 1 is a horizontal sectional view of a rectangular hollow pipe antenna according to one embodiment of the invention.

Fig. 2 is a vertical side elevation of part of the antenna according to the present invention.

Fig. 3 is a horizontal sectional view of another embodiment of the invention as applied to a streamlined or tear-drop shaped hollow-tube antenna.

Fig. 4 is a horizontal sectional view of a modification of the antenna of Fig. 3.

Figs. 5 and 6 are horizontal sectional views of still other modifications; and

Fig. 7 is a partly broken away perspective view of the antenna of Fig. 6.

Referring now to Figs. 1 and 2 there is shown, by way of example, a beacon antenna 10 comprising a hollow pipe 11 of substantially rectangular cross-section which has its longitudinal axis vertical when the antenna is in its contemplated vertical operating position such as extending from the skin surface of an aircraft or other support. As shown, pipe 11 is in the form of a wave guide and is of suitable dimensions to entertain the usual modes of energy wave propagation therein. Preferably for good radiation pattern distribution, the wider dimension *b* should be short relative to the wavelength of the energy in pipe 11 at the desired frequency of operation. Each of the opposite broad side walls 12 of pipe 11 are provided substantially centrally of the width thereof and approximately on the center line thereof, with a longitudinal vertical slot 13 of identical shape and dimensions. The slots may be approximately $3\lambda/4$ long and their degree of narrowness may be determined to control to a certain extent the bandwidth of the antenna. The slots 13 are so excited that the emitted radiation from one slot 13 is preferably 180° out of phase with its opposite slot. To aid radiation through slots 13, probes 14, which may be adjustable as to depth of penetration in pipe 10, may be located close to and approximately centrally of, either or both edges of each slot depending on the energy mode within pipe 10 and the phasing desired.

If desired a plurality of sections of pipe 11 may be mounted in aligned relation to form an array. In such an array arrangement, the slots 13 on each side of pipe 10 are preferably aligned with their centers spaced apart by approximately one half of the wavelength of energy in the pipe 11 and with their phase of excitation alternately reversed or they may be a full wavelength apart with no phase reversal. In the former case the

slots 13 are preferably approximately $\lambda/2$ long. In either case, the adjacent aligned slots 13 of the array will radiate energy approximately in phase with each other but in opposite phase to the radiation from slots 13 on the opposite side of pipe 11.

In Figs. 3, 4, 5 and 6 there are shown four modified forms of the invention in which the antenna 10 comprises a hollow pipe or tube 15 of tear-drop shape (streamlined) in cross-section. The arrangement of the slots is similar to that described with reference to Fig. 1, the longitudinal axes of the slots 13 being approximately coincidental with the centerline of the two opposite sides 16. In Fig. 3 the probes 14 are located in the same manner as in Fig. 1, that is on the same side of a plane through the longitudinal axes of slots 13.

The antenna of Fig. 4 is in the form of a coaxial conductor transmission line having a central conductor 17 located approximately along the axis of the spaced pipe 15. The probes 14 in this modification are both on the far sides, or, as shown on the opposite sides of a plane through the longitudinal axes, of slots 13 assuming the current flow as indicated by the arrows. If desired pipe 15 may be filled with a dielectric material 15'.

Fig. 5 shows a further modification in which the exciting energy is fed to antenna 10 by means of a balanced two wire feed, the wires 18 and 19 thereof being of opposite polarity. Wires 18 and 19 are connected to opposite sides of slots 13 by means of connecting wires or rods 20 and 21 respectively, the connections being reversed for one of the slots 13 to provide proper phase relationship.

In the modification illustrated in Figs. 6 and 7 the energy is fed to antenna 10 by a coaxial conductor line 22 terminating in dipole sections 23 and 24, section 23 connecting the center conductor 25 with the edge of one of slots 13, while section 24 connects the outer conductor with edge of other opposite slot 13, these sections taking the place of the probes 14, hereinbefore described. The outer conductor 26 of line 22 is provided with diametrically opposed slots 27 extending longitudinally from the end thereof for a distance of approximately $\lambda/4$ to provide impedance matching with the balanced dipole sections 23 and 24.

In Fig. 6 there is shown a partition 28 which extends longitudinally of member 15 substantially parallel to the plane through the slots 13. Such a partition 28 may be included in all of the modified forms of the invention and so positioned as to provide proper internal dimensions of the member for proper modeing of energy propagated therein.

While there has been described what is at present considered the preferred embodiments of this invention, it will be obvious to those skilled in the art that various changes and modifications may be made herein without departing from the invention.

What is claimed is:

1. An antenna for radiating and receiving waves of electromagnetic energy in a substantially uniform omnidirectional energy pattern in a plane, comprising a tubular member of an electrically conducting material and of non-circular cross-section, the walls of said member on opposite sides of the major axis of said cross-section each having a slot disposed longitudinally of said member, and means positioned in said member to

cause propagation of electromagnetic energy therein in a mode with at least a component of the electric field across said slots in said cross-section and 180° out of phase on opposite sides of said major axis.

2. An antenna as claimed in claim 1 wherein said member is a hollow pipe wave guide of rectangular cross-section and wherein said means comprises a probe extending inwardly from the edge portion of each slot at substantially midway of the length thereof, said probes being on the same side of a plane through the longitudinal axes of said slots.

3. An antenna as claimed in claim 1 wherein said member is a hollow wave guide having its cross-section substantially in the shape of a tear-drop and wherein said means comprises a probe extending inwardly from the edge portion of each slot at substantially midway of the length thereof, said probes being on the same side of a plane through the longitudinal axes of said slots.

4. An antenna as claimed in claim 1 wherein said member is of streamlined shape in cross-section, in which a solid conductor extends longitudinally within said member with its axis substantially coinciding with the longitudinal axis of said member, said member thereby comprising the outer conductor to form with said solid conductor a coaxial conductor transmission element for said energy and wherein said means comprises a probe extending inwardly from the edge portion of each said slot at substantially midway of the length thereof, said probes being on opposite side of a plane through the longitudinal axis of said slots.

5. An antenna as claimed in claim 1 wherein said member is of tear-drop shape in cross-section and includes a balanced two-wire conducting line extending longitudinally within said member for feeding energy to said member, and wherein said means comprises a conductor connecting one of said wires to one edge of each of said slots and a conductor connecting the other wire to the opposite edge of each slot, the connections to one of said slots being reversed with respect to the connections to the other slot.

6. An antenna as claimed in claim 1 wherein said member is of streamlined shape in cross-section and includes a coaxial conductor transmission line extending longitudinally within said member, the axis of said coaxial line substantially coinciding with the longitudinal axis of said member, and wherein said means comprises a dipole termination of said coaxial line, one of the sections of said dipole connecting the central conductor of said coaxial line to the edge portion of one of said slots, the other section of said dipole connecting the outer conductor of said coaxial line to the edge portion of the other slot, said connections to the edges of said slots being on the same side of a plane through the longitudinal axes of said slots.

7. An antenna for radiating energy in a substantially uniform omnidirectional radiation pattern in a plane comprising a hollow pipe member of electrically conductive material, said member being of non-circular cross-section and having a pair of broad walls on opposite sides of the major axis of said cross-section, each of said broad walls having a slot disposed longitudinally of said member and substantially along the centerline of each of said broad walls whereby said slots are directly opposite each other, and means for coupling each of said slots to energy propagated within said member whereby said

slots are adapted to be excited by, and to radiate, said energy, said means being so positioned relative to said slots that the excitation of one of said slots is 180° out of phase with that of the other slot of said member.
